US00D861677S

(12) **United States Design Patent** (10) Patent No.: **US D861,677 S**
Wu (45) Date of Patent: ** Oct. 1, 2019

(54) **SMARTWATCH**

(71) Applicants: **HUIZHOU DESAY INDUSTRIAL RESEARCH INSTITUTE CO., LTD.**, Guangdong (CN); **MPOW TECHNOLOGY CO., LIMITED**, Hong Kong (HK)

(72) Inventor: **Yingtin Wu**, Guangdong (CN)

(73) Assignees: **HUIZHOU DESAY INDUSTRIAL RESEARCH INSTITUTE CO., LTD.**, Guangdong (CN); **MPOW TECHNOLOGY CO., LIMITED**, Hong Kong (HK)

(**) Term: **15 Years**

(21) Appl. No.: **29/642,325**

(22) Filed: **Mar. 29, 2018**

(30) **Foreign Application Priority Data**

Dec. 19, 2017 (CN) 2017 3 0651930
(51) LOC (12) Cl. **14-02**
(52) U.S. Cl.
USPC **D14/344**
(58) **Field of Classification Search**
